US00D796540S

(12) **United States Design Patent** (10) Patent No.: **US D796,540 S**
 McLean et al. (45) Date of Patent: ** Sep. 5, 2017

(54) **DISPLAY SCREEN WITH GRAPHICAL USER INTERFACE FOR MOBILE CAMERA HISTORY HAVING EVENT-SPECIFIC ACTIVITY NOTIFICATIONS**

(71) Applicant: **GOOGLE INC.**, Mountain View, CA (US)

(72) Inventors: **Melissa McLean**, Novato, CA (US); **Michael Mizoni**, Mountain View, CA (US); **Lauren Von Dehsen**, San Francisco, CA (US); **Joe Delone Venters**, Alameda, CA (US); **Tracy Kuwatani**, Mountain View, CA (US); **Zachery Kennedy**, San Jose, CA (US); **Tomas Brennessl**, Palo Alto, CA (US)

(73) Assignee: **GOOGLE INC.**, Mountain View, CA (US)

(**) Term: **15 Years**

(21) Appl. No.: **29/530,440**

(22) Filed: **Jun. 16, 2015**

CLAIM

An ornamental design for a display screen with graphical user interface for mobile camera history having event-specific activity notifications, as shown and described.

DESCRIPTION

This application is related to the following applications, all of which are hereby incorporated by reference in their entirety:

U.S. patent application Ser. No. 29/530,441, titled “User Interface for Mobile Camera History Having Collapsible Video Events,” filed Jun. 16, 2015;

U.S. patent application Ser. No. 29/530,442, titled “User Interface for Monitoring and Controlling Remote Video Camera,” filed Jun. 16, 2015;

U.S. patent application Ser. No. 14/738,928, titled “Methods and Systems for Smart Home Automation Using a Multi-function Status and Entry Point Icon,” filed Jun. 14, 2015;

U.S. patent application Ser. No. 14/739,412, titled “Methods and Systems for Presenting Alert Event Indicators,” filed Jun. 15, 2015; and

U.S. patent application Ser. No. 14/739,427, titled “Methods and Systems for Presenting a Camera History,” filed Jun. 15, 2015.

FIG. 1 is a front view of the first image in a sequence for a display screen with graphical user interface for mobile camera history having event-specific activity notifications showing our new design;

FIG. 2 is a second image thereof;

FIG. 3 is a third image thereof;

FIG. 4 is a fourth image thereof;

FIG. 5 is a fifth image thereof; and

FIG. 6 is a sixth image thereof.

FIG. 7 is a front view of the first image in a sequence for a display screen with graphical user interface for mobile camera history having event-specific activity notifications showing another embodiment of our new design;

FIG. 8 is a second image thereof;

FIG. 9 is a third image thereof;

FIG. 10 is a fourth image thereof;

FIG. 11 is a fifth image thereof; and,

FIG. 12 is a sixth image thereof.

The broken line showing of a display screen and elements of a graphical user interface is included for the purpose of illustrating portions of the article and forms no part of the claimed design.

The appearance of the animated images sequentially transitions between the images shown in FIGS. 1-6, and between the images shown in FIGS. 7-12. The process or period in which one image transitions to another forms no part of the claimed design.
